DECK OF PLAYING CARDS

Thomas B. Stauff, deceased, late of Minneapolis, Minn., by Alma B. Stauff, executrix, Minneapolis, Minn.

Application December 14, 1956, Serial No. 44,780

Term of patent 14 years

(Cl. D34—13)

FIG. 12

FIG. 13

FIG. 14

FIG. 15

FIG. 16

FIG. 17

FIG. 18

FIG. 19

FIG. 20

FIG. 21

FIG. 22

FIG. 23

Figs. 1-10 inclusive, are face views of the ace and spot cards of the diamond suit;

Fig. 11 is a face view of the joker;

Fig. 12 is a face view of the jack of hearts;

Fig. 13 is a face view of the queen of hearts;

Fig. 14 is a face view of the king of hearts;

Fig. 15 is a face view of the jack of diamonds;

Fig. 16 is a face view of the queen of diamonds;

Fig. 17 is a face view of the king of diamonds;

Fig. 18 is a face view of the jack of clubs;
